UNITED STATES PATENT OFFICE.

JOHN WALKER TILTON, OF ATLANTIC CITY, NEW JERSEY.

CURTAIN-FASTENER.

1,131,293.

Specification of Letters Patent.

Patented Mar. 9, 1915.

Application filed October 14, 1913. Serial No. 795,120.

To all whom it may concern:

Be it known that I, JOHN WALKER TILTON, a citizen of the United States, residing at Atlantic City, Atlantic county, New Jersey, 5 have invented certain new and useful Improvements in Curtain-Fasteners, of which the following is a specification.

The invention relates generally to curtain-fasteners, but is more particularly designed 10 for the curtains of automobiles, and is an improvement on the curtain-fastener described and illustrated in an application filed by me November 26, 1912, Serial Number 733,665.

15 The prime object of the invention is to simplify and cheapen the cost of construction of this type of fastener, without impairing its durability or its effectiveness in operation.

20 The invention consists in the novel construction and peculiar arrangement of the several parts, as will be hereinafter fully described in this specification and briefly set forth in the claims.

25 In the drawings—Figure 1 is a side elevation of my improved fastener; Fig. 2, a vertical section of the same; Fig. 3, a perspective view of the base-plate; Fig. 4, a similar view of the spring spider, detached, and Fig. 30 5, a side of the tubular post and rod.

Referring to the several views, the numeral 1 indicates the base-plate which is provided with a central boss 2, preferably struck up out of the base-plate, so as to provide a cavity 3 therein. The boss is centrally apertured, and passing therethrough is a tubular post 4, through which passes a vertically movable securing-rod 5. Mounted on the upper end of the tubular-post and setting 40 over the upper end of the securing-rod is a spider 6 having a plurality of downwardly-extending spring-arms 7, and seated above the spider is a spring 8, preferably a coil-spring. The ends of the spring-arms curve 45 outwardly and resting upon them is the bottom edge of a vertically-slidable cap 9, having a perforation in the top thereof, through which the upper reduced end of the securing-rod projects and is upset, as is also the lower 50 end of said rod. Thus it will be seen that the several parts are securely held together,

the cap, tubular post, and securing rod, the latter having a slight vertical movement. The base-plate is provided with holes 10 through which screws may be passed for securing the fastener to the top or body of a carriage automobile, or other vehicle. 55

The operation of the fastener is obvious; to fasten a curtain, all that is necessary is to pass the eyelet in the curtain over the cap, 60 pressing in the springs. As soon as the eyelet passes over the spring-arms, they immediately spring out confining the curtain. To release the curtain, the cap is pushed down, which forces the spring-arms inward out of 65 engagement with the curtain.

Having thus described my invention, what I claim is:—

1. A curtain-fastener, comprising an attaching-plate provided with an integral, hollow boss having a central aperture, a tubular post fitted to the apertured boss, a spring-arm spider seated upon the tubular post, and a headed operating-rod slidable in the tubular post, and a spring-pressed cap secured to 70 the slidable rod, and adapted when operated to force the arms of the spider inward, so as to permit an object confined between the ends of the spring-arms and the hollow boss 75 to be released. 80

2. A curtain-fastener, comprising an attaching-plate provided with an integral, hollow boss having a central aperture, a sleeve attached to the apertured boss, a spring-arm spider seated upon the sleeve, a movable rod 85 operative through the sleeve and spider, a cap secured to the movable rod, said cap adapted when operated to force the spring-arms of the spider inward to release the curtain confined between the ends of 90 said arms and the hollow boss, means for limiting the movement of the rod in one direction, and a spring interposed between the spider and cap for returning said rod and cap to normal position. 95

In testimony whereof I affix my signature in presence of two witnesses.

JOHN WALKER TILTON.
